Application July 29, 1955, Serial No. 525,301

10 Claims. (Cl. 222—139)

2

lar to Fig. 2, but showing a further modification of the invention.

Before explaining in detail the present invention, it is to be understood, that the invention is not limited in its application to the details of construction and arrangement of parts illustrated in the accompanying drawing, since the invention is capable of other embodiments and of being practiced or carried out in various ways. Also, it is to be understood, that the phraseology and terminology employed herein is for the purpose of description and not limitation.

In the drawings the dispenser is generally indicated by the numeral 10, and comprises an upper body portion 11, and a base portion 12. The upper or body portion 11 is preferably made from a solid block of plastic, suitable, light-weight metal, or other like material, and is provided with an upwardly extending flange 14 on the rearward edge of the upper side, which may be secured to a wall, as by the screws 16.

15 As best seen in Fig. 2, the body portion 11 is provided with a pair of spaced apart vertically disposed bores 18 and 20, adapted to form a pair of storage chambers for an alloy 22 and mercury 24, respectively. The storage chambers 18 and 20 are open at the top of the body portion 11 and are provided with suitable covers 26 and 28, respectively, which may be made from any suitable plastic and may be secured in said chambers by a press fit. The lower ends of the chambers 18 and 20 are tapered downwardly and inwardly as indicated by 25 the numerals 30 and 32, respectively. The lower tapering end portions of the chambers 18 and 20 communicate with a pair of upper outlet ports 34 and 36, respectively, which extend downwardly and communicate with a transverse bore 38, which passes completely through 30 the body portion 11.

35 Rotatably mounted in the bore 38, is a cylindrical shaft or rotary valve 40 having a pair of spaced apart pockets 42 and 44, which are adapted to register with the upper outlet ports 34 and 36, respectively, when the 40 rotary valve 40 is turned to a first position. A second pair of lower outlet ports 46 and 48 are provided in the body portion 11, below the transverse bore 38, and, in alignment with the upper ports 34 and 36, respectively. The pockets 42 and 44 are adapted to register with the lower outlet ports 46 and 48, respectively, when the 45 rotary valve 40 is turned to a second position.

46 The outer ends of the rotary valve 40 are each provided with an outwardly extending threaded extension 50 and 52, on which are threadably mounted the knobs 54 and 56, respectively, which knobs serve to abut the 50 sides of the body portion 11 and retain the rotary valve 40 in the proper axial position. The one knob 56 has an integral handle 58 adapted for rotating the rotary valve 40.

55 A pair of stops 60 and 62 are mounted in the side of the body portion 11, in positions which are 180° apart, and, said stops function to limit the rotary movement of said handle 58. One end of the transverse bore 38 is provided with an enlarged part 63 in which is operatively 60 mounted a coil spring 64, adapted to fit over the rotary shaft 40 and to have one end 66 fixed to the body portion 11, and the other end 68 fixed in the knob 56.

65 The rotary valve 40 is provided with an axial aperture 70, which is in alignment with a similar aperture 72 through the knob 56, and, in which apertures is threadably mounted an elongated screw 74. The forward end of the adjustable screw 74 is adapted to protrude into the mercury pocket 44, whereby, the size or volume of the pocket 44 may be changed, as desired, by merely 70 threading the screw 74 inwardly and outwardly of said pocket.

As shown in Figs. 2 and 3, the base portion 12 is pro-

This invention relates generally, to improvements in dispensing devices, and, more particularly, to an improved type of such device wherein means are provided for measuring, mixing and dispensing predetermined quantities of a plurality of ingredients, such as dental alloys, mercury and the like, for use in the preparation of dental amalgam, and for other like purposes.

The principal object of this invention is the provision of a dispenser of the aforementioned class, which shall be simple and inexpensive of construction, economical of manufacture, durable and efficient in operation.

It is another object of this invention to provide a dispensing device for dispensing simultaneously a plurality of predetermined quantities of various ingredients, from storage chambers in the dispenser, so as to produce a proper mixture of such ingredients for ready use thereof.

It is a further object of this invention to provide a dispensing device of the above mentioned general character comprising, a body portion provided with a pair of vertically disposed, spaced apart bores in the upper end thereof, cover means enclosing the upper end of said vertical bores, a transverse bore in said body portion below said vertical bores, a first pair of openings in said body portion between said transverse bore and each of said vertical bores, a rotatable shaft mounted in said transverse bore, means for rotating said shaft, a pair of pockets in said shaft and adapted to register with said openings, a funnel fixed on the lower side of said body portion, and, a second pair of openings in said body portion below said transverse bore and adapted to register with said pockets and said funnel.

It is a further object of this invention to provide adjustable means coacting with one or more of the ingredient holding chambers and the rotary controlling valve therefor, whereby the predetermined quantity of such ingredient or ingredients may be varied as desired to produce the desired proper mixture.

It is a still further object of this invention to provide a dispenser of this class, which is compact and attractive in form, and, which can be conveniently mounted on a wall or table for ready use thereof.

Other objects, features and advantages of this invention will be apparent from the following detailed description and appended claims, reference being had to the accompanying drawing forming a part of the specification wherein like reference numerals designate corresponding parts of the several views.

In the drawings:

Fig. 1 is a perspective view of an illustrative embodiment of the invention;

Fig. 2 is an elevational sectional view of the structure illustrated in Fig. 1, taken along the line 2—2 thereof;

Fig. 3 is a perspective view of the base portion of the illustrative embodiment;

Fig. 4 is an elevational sectional view of a modified rotary valve used in the invention; and,

Fig. 5 is a fragmentary elevational sectional view simi-

vided with a plurality of screw holes 76 therethrough, which are adapted to register with similar screw holes 78 in the lower surface of the body portion 11. A plurality of suitable screws 80 are adapted to be threaded in the screw holes 76 and 78, so as to fixedly secure the base 12 to the body portion 11.

It will be noted, that the alloy ports 34 and 46 are larger than the mercury ports 36 and 48, because a greater quantity of alloy is used in making the final mixture. The base portion 12 is provided with a vertical opening 82, which passes completely through the said base portion, and, which is disposed immediately below the lower alloy port 46. A chute 84 is formed in the base portion 12, immediately below the mercury port 48. The chute 84 tapers downwardly from a point immediately below the mercury port 48 and empties into the vertical opening 82. A spout 86 is fixedly mounted on the lower side of the base portion 12, by any suitable means, and, is in registration with the opening 82. For decorative purposes, the sides of the base portion 12 may be provided with a plurality of grooves 87 around the periphery thereof.

In the practice of the invention, the chambers 22 and 24 would be filled with alloy and mercury, respectively. The coil spring 64 biases the handle 58 into an upper position against the upper stop 62, as shown in Fig. 2. When the handle 58 is in said upper position, the pockets 42 and 44 register with the ports 34 and 36, respectively, and are filled with ingredients from the storage chambers. When the handle 58 is moved in a counter clockwise direction, as viewed from the right side of Fig. 2, and downwardly into engagement with the lower stop 60, the pockets 42 and 44 will register with the lower ports 46 and 48, respectively, and, the ingredients in said pockets will pass into the opening 82, and the chute 84, and thence downwardly into the discharge spout 86 and into a suitable container for further operations thereon. It will be understood, that the opening 82, in the base portion 12, and the spout 86, are preferably placed directly beneath the alloy port 46, since the alloy has a tendency to pile up on any sloping surface. When the operator releases the handle 58, the spring 64 will rotate the rotary valve 40, so as to bring the pockets 42 and 44 into registration with the upper ports 34 and 36, respectively. The rotary valve 40 will be rotated until the handle 56 abuts the upper stop 62.

Fig. 4 discloses a modified rotary valve 40, in which the pockets 42 and 44 are provided with threaded plugs 88 and 90, respectively, in the lower ends thereof. The threaded plugs 88 and 90 are provided with cross slots 92 and 94, respectively. The aforementioned plugs may be adjusted upwardly and downwardly by means of a screwdriver being fitted into the slots 92 and 94, and turning the plugs, so as to adjust the size of said pockets. The dispenser may be disassembled for the adjustment of said threaded plugs, or, a screwdriver may be passed downwardly through the storage chambers and into the pockets for adjustment of said plugs.

Fig. 5 discloses a further modification of the invention in which a bearing sleeve 96 is provided between the rotary valve 40 and body portion 11.

It will be seen, that the present invention provides a dental dispensing device for dispensing a predetermined quantity of alloy and mercury, or other like ingredients, and, which device is simple and compact, and which may be made with few precision parts.

While it will be apparent that the preferred embodiments of the invention herein disclosed are well calculated to fulfill the objects above stated, it will be appreciated that the invention is susceptible to modification, variation and change without departing from the proper scope of fair meaning of the subjoined claims.

What is claimed is:

1. A device of the class described, comprising: a

body portion provided with a pair of vertically disposed, spaced apart bores; said bores extending to the upper surface of said body portion and being open to the atmosphere at said surface; means for covering the upper ends of said bores; a transverse bore in the lower part of said body portion communicating with the lower ends of said vertical bores; a shaft rotatably mounted in said transverse bore; a knob threadably mounted on one end of said shaft adapted to abut one side of said body portion; a handle forming knob threadably mounted on the other end of said shaft adapted to abut the other side of said body portion; stop means mounted on said body portion to limit rotation of said handle forming knob; spring means interconnecting said body portion and handle forming knob for biasing said handle forming knob into a predetermined position; a pair of spaced apart pockets in said shaft arranged to register with the lower ends of said vertical bores when the shaft is in a first position; a base fixedly mounted on the lower side of

10 said body portion; a funnel formed in said base; a pair of ports in the lower side of said body portion below said shaft and adapted to register with the pockets in said shaft when said shaft is turned to a second position; and, said ports being in communication with said funnel.

15 2. A device of the class described, comprising: a body portion provided with a pair of vertically disposed, spaced apart bores; said bores extending to the upper surface of said body portion and being open to the atmosphere at said surface; means for covering the upper ends of said bores; a transverse bore in the lower part of said body portion communicating with the lower ends of said vertical bores; a shaft rotatably mounted in said transverse bore; a knob threadably mounted on one end of said shaft adapted to abut one side of said body portion; a handle forming knob threadably mounted on the other end of said shaft adapted to abut the other side of said body portion; stop means mounted on said body portion to limit rotation of said handle forming knob; spring means interconnecting said body portion and handle forming knob for biasing said handle forming knob into a predetermined position; a pair of spaced apart pockets in said shaft arranged to register with the lower ends of said vertical bores when the shaft is in a first position; a base fixedly mounted on the lower side of said body portion; said base having an opening extending therethrough; said opening being provided with a spout on the outer side thereof and being in communication with one of said bores; and a chute communicating with the other of said bores and with said opening.

20 3. The invention as set forth in claim 2, wherein: said shaft is provided with a threadably mounted axially extending screw which extends through the handle forming knob and into said shaft and into one of said pockets and is adjustable so as to permit manual variation of the size of said one pocket by threading said screw inwardly or outwardly of said one pocket.

25 4. The invention as set forth in claim 3, wherein: a bearing sleeve is mounted between said shaft and said body portion.

30 5. In a device of the class described, the combination of: a body portion; a pair of spaced apart vertical bores in said body portion extending inwardly from the upper side thereof; means for covering the upper ends of said bores; a transverse bore in the lower part of said body portion; a first pair of ports in said body portion interconnecting said vertical bores and said transverse bore; one of said ports being of a larger diameter than the other; a shaft rotatably mounted in said transverse bore; a second pair of ports in said body portion below said transverse bore which are equal in size to the first pair of ports and in alignment therewith and which communicate with said transverse bore; a pair of spaced apart pockets in said shaft arranged to register alternately with the first pair of ports and the second pair of ports during the rotation of the shaft; a base fixedly mounted

on the lower side of said body portion; said base having an opening extending therethrough and disposed in alignment with the larger ports of said first and second pair of ports; a spout mounted on the lower end of said opening; a chute in said base having the upper end thereof in communication with the smaller of the second pair of ports, and the lower end thereof in communication with said opening in said base.

6. The invention as set forth in claim 5, wherein: said shaft is provided with retaining means on each end thereof to retain said shaft in said body portion; a handle on one of said retaining means; stop means on said body portion for limiting the rotation of said shaft; spring means interconnected between said body portion and said handle for normally maintaining said handle in a predetermined portion; and, means for adjusting the size of one of said pockets.

7. The invention as set forth in claim 6, wherein: said means for adjusting the size of one of said pockets comprises a plug threadably mounted in the lower end of said pocket.

8. The invention as set forth in claim 6, wherein: said means for adjusting the size of one of said pockets comprises a screw threadably mounted in said shaft so as to be adjustably engageable with said one pocket.

9. A device of the class described, comprising: a body portion provided with a pair of vertically disposed, spaced apart bores in the upper end thereof; cover means en-

closing the upper end of said vertical bores; a transverse bore in said body portion below said vertical bores; said body portion having a first pair of openings between said transverse bore and each of said vertical bores; a rotatable shaft; a pair of pockets in said shaft and adapted to register with said openings; a funnel fixed to the lower side of said body portion; and said body portion having a second pair of openings below said transverse bore and adapted to register with said pockets and said funnel.

10. The invention as set forth in claim 9, wherein: said device is provided with means for adjusting the size of said pockets.
